LIQUID DISPENSER

George Reisinger and Joseph Farkas,
Rochester, N. Y.

Application October 15, 1937, Serial No. 169,304

3 Claims. (Cl. 225—2)

This invention relates to liquid dispensing means and has for its principal object to provide a container with a self-contained dispenser which permits the dispensing of the contents in a convenient, quick and sanitary manner and therefore eliminates the use of auxiliary tapping devices and the loss of some of the contents due to the leakage which is unavoidable during the tapping operation.

Another object of this invention is to provide a dispenser which is constructed and mounted for shipment with the container to be supplied to the consumer ready for instant use.

A further object of this invention is to provide the container with a dispenser including a dispenser intake tube and intake well to make possible the dispensing of practically all of the contents of the keg or barrel.

All these and other objects of this invention and attendant advantages will become more readily apparent from the detailed description thereof which follows, reference being had to the accompanying drawings in which.

Figure 1 is a longitudinal section of portions of a barrel or keg and the novel dispenser carried thereby.

Figure 2 is a top plan view of the dispenser and the barrel or keg portion surrounding it.

Figure 3 is a top plan view of a modified form of the dispensing valve.

Figure 4 is a vertical sectional view of the valve taken on the line 4x—4x of Figure 3.

Figure 5 is a vertical sectional view of another modified form of the dispensing valve.

In the figures like reference numerals indicate like parts.

The dispenser, forming the subject matter of this invention, is adapted to be incorporated in the container in such a manner that it forms a part thereof whether the container is full or empty. For this reason the dispenser need not be removed from the container except when the container is being cleaned or filled. The dispenser is also provided with novel means which permit the removal of substantially all of the contents thru the dispenser.

The container in the form of a keg or barrel 1, illustrated in conjunction with the novel dispenser, is shown constructed of wood although, of course, it is equally applicable to a steel keg or barrel or any other liquid containers.

The head 2 of the barrel or keg is provided with the tap bush 3 which is suitably threaded into the head to provide the recess or pocket 4 there-

5 swinging protective cover 5 or any other cover with which the recess is closed during the shipment of the keg or barrel or the storage thereof. The dispenser construction proper comprises the valve body 6 which is threaded into the 10 reduced extension of the bush so as to have its flange 7 rest on the bottom of the recess and seal the valve body into the bush. To facilitate the threading of the valve body into and out of the bush, its top is shaped above the flange 7 so that it may be readily turned by means of a suitable wrench or other tool. Suitable recesses 8 may also be provided in the body 6 so that a 15 spanner wrench or other tool may engage therein for threading the valve body in or out of the bush.

The tapered valve shank 9 of the dispenser is eccentrically located in the valve body and is mounted to turn in the tapered bore 10. The valve shank has a central vertical duct 11 and 20 a horizontal inlet 12 for the passage of the liquid therethru. The horizontal inlet is located for movement into and out of register with the port opening 13 in the valve body 6 for opening and closing the dispenser.

25 The upper portion of the valve shank is shaped at 14 to provide for its turning by means of a suitable wrench. A threaded extension 15 at the top of the shank serves as connecting means for a dispensing tube or hose 16 with which the 30 dispenser is piped to the bar or the receptacle to be filled.

The valve shank is held seated in its tapered bore by means of the nut 17 which is threaded to the bottom of the shank and a spring 18 is 35 interposed between the nut and the bottom of the valve body to yieldingly draw the shank into its bore.

A nipple 19 is threaded to the valve body so 40 as to encase the bottom of the valve shank and provide an extension for the recess 20 leading from the inlet opening 13 and support the intake tube 21 suspended therefrom. The latter is suitably threaded or otherwise mounted in the nipple so as to extend the full length of the barrel into the intake well 22. This well is formed by a hollow plug 23 which is suitably threaded into the bottom head 24 or otherwise held in line with the tap bush 3 in the upper head 2 of the container. One or more inlet openings 25 are provided in the wall of the inlet tube near the bottom of the well in order to provide the only intake for the dispenser within the well to permit the withdrawal of all of the fluid contents of the bar- 45 50 55

rel above the bottom of the container. Thus none of the liquid contents is wasted.

Air under pressure is used to force the liquid contents thru the dispenser and for this purpose a check valve 26 is mounted in the valve body 6 with an outlet into the keg or barrel on the outside of the nipple 19 and its intake tube 21. Air is forced into the barrel thru this valve on top of the liquid contents thereof to force the liquid contents into the intake tube at the bottom of the barrel or keg. A pump or other air pressure supply may be suitably connected to the check valve to furnish the air pressure for the dispensing of the contents thru the dispenser.

From the foregoing it will be apparent that each barrel or keg or other container may be provided with its own dispensing equipment at the filling station and be transported for immediate use by the consumer. The dispensing equipment is constructed and mounted so that it is entirely concealed in the top bush and therefore cannot be damaged while transporting the barrel. When the barrel or keg is empty, it is returned with the dispensing equipment and is then efficiently washed and cleaned by any suitable means, as for example by having the steam used for cleaning the barrel also used for cleaning the dispenser either while mounted in the barrel or after being removed therefrom. After the barrel or keg is cleaned, the dispenser may be used to fill it by connecting the liquid supply to the valve shank and keeping the check valve open until the keg is filled.

Figures 3 and 4 illustrate a modified form of the dispenser in which the valve body is provided with a separate connecting nipple 26 for the hose connection with which the dispenser is piped to the bar. In this modification the valve shank 9 is slotted at the top at 27 so that a screw driver

may be conveniently used to open and close the valve.

Still another modification is illustrated in Figure 5 in which the valve stem is mounted in the valve body at an angle so that the valve stem 9 5 can be provided with a handle 28 for the movement thereof in the recess formed by the bush.

A tube 30 for charging the contents of the barrel after it is filled may be attached to the valve body in line with the check valve 26.

We claim:

1. In a dispenser the combination of a hollow bush having a threaded opening of reduced diameter in the bottom thereof, a valve body entirely encased by said bush, means surrounding said valve body and movable within said bush for rotation of said valve body in threading it in and out of the opening in the bottom of said bush, a hollow valve stem rotatably mounted in said valve body, means carried by said hollow valve stem within said bush for the operation thereof and the control of the flow of liquid through the dispenser within the bush and hose connecting means with said valve stem carried by said valve body within said bush.

2. In a dispenser as set forth in claim 1 including an air inlet thru said valve body, a check valve carried by said valve body within said bush and a hose connection for said check valve surrounded by said bush.

3. In a dispenser the combination as set forth in claim 1 including a protective cover mounted to swing on said bush so as to cover and uncover the valve body, its valve stem and hose connection in said bush, an intake tube, and means provided at the bottom of said valve for the support and suspension of said tube in an intake well.

GEORGE REISINGER.
JOSEPH FARKAS.
